UNITED STATES PATENT OFFICE.

VERN EARNEST REICHARD, OF STINNETT, TEXAS.

PUMPING APPARATUS.

Application filed August 16, 1927. Serial No. 213,358.

This invention relates to pumping apparatus and more particularly to a method of installing pump tubing into well casings.

An important object of the invention is the provision of a structure such that the use of well tubing extending entirely to the top of the well casing is eliminated and a section of tubing substituted therefor which is just sufficient to extend from the bottom of the well to a point slightly above the lower end of the well casing.

A further object of the invention is to provide a structure of this character permitting ready insertion and removal of the tubing section.

A still further object of the invention is to provide a construction of this character which embodies means for automatically dumping the tubing section to permit the fluid above the section to pass the lower end of the well when the tubing section may be pulled.

A still further object of the invention is the production of a fishing tool whereby the tubing section may be readily inserted and removed.

These and other objects I attain by the construction shown in the accompanying drawings, wherein for the purpose of illustration is shown a preferred embodiment of my invention and wherein:

Figure 1 is a vertical sectional view showing pumping apparatus constructed in accordance with my invention in position in the well, a fishing tool being illustrated in position to remove the apparatus;

Figure 2 is an enlarged sectional view through the seal at right angles to the view of Figure 1;

Figure 3 is a transverse section through the pumping apparatus in alignment with the fishing tool.

Referring now more particularly to the drawings, the numeral 10 generally designates a well casing, the lower end of which is spaced from the bottom of the well bore, indicated at 11. In accordance with my invention, I provide a tubing section 12 adapted to rest upon the lower end 11 of the well bore and extend to a point slightly above the lower end of the casing. This tubing section 12 includes the usual working barrel of oil well pumping apparatus and serves as a foot valve for the pump, the lower end thereof including a screen. At this point, the upper end of the tubing section is threaded into a collar 13,

the upper end of which forms a seat for a swab rubber 14 and the body of which is provided with gas valves 15. These valves only open when the gas pressure exceeds a predetermined amount being held seated by springs. The action of the well pump has no effect upon the operation thereof. Threaded in the upper end of this collar is a short nipple 16 forming a continuation of the tubing and secured to the upper end of this short nipple is a collar 17 which is exteriorly threaded and has mounted thereon an adjusting nut 18, by means of which a disk 20 for the swab rubber 14 is adjusted to regulate the tension of the swab rubber upon the walls of the well casing. The disk 20 is provided with openings 21 permitting the passage of gas and threaded in the upper collar 17 is a nipple 22 forming a further continuation of the tubing.

The upper end of the tubing nipple 22 is threaded into a setting and pulling tool, generally designated at 23. This setting and pulling tool comprises a body having a bore 24, the lower end of which tapers downwardly, as indicated at 25, to the diameter of the tubing. At its upper end, the bore is suddenly reduced to form a downwardly facing shoulder 26 and above this shoulder, increases in diameter upwardly to provide a funnel mouth 27. Beneath the shoulder 26 is disposed a ring 28, which is normally urged downwardly by a spring 29 and has secured thereto rods 30, which pass through openings formed in the setting and pulling tool 23, the disk 20 and lower collar 13 of the swab and are secured at their lower ends to a sleeve valve 31 controlling a slot 32 formed in the wall of the casing.

A fishing tool therefor is provided comprising a pair of depending arms 33 connected at their upper ends by a member 34 adapted, as at 35, for connection with a rod R or cable whereby it may be manipulated. The lower ends of these arms which are normally held apart by their own resiliency are formed with spurs or hooks 36 adapted to engage the under face of the ring 28 and so support the setting tool and the tubing section carried thereby. Each arm has upon its outer face a lug 37 and loosely surrounding the arms above these lugs is a sleeve 38.

The operation in installing the tubing section is as follows: The swab elements are first adjusted, so that the swab rubber will have

proper tension against the casing section in which it is to be seated. The fishing tool is then engaged in the upper end of the combined setting and pulling tool 23 with the 5 prongs 36 engaged beneath the lower face of the ring. The sleeve 38 loosely surrounds the arms above the lugs and with the parts in these positions, the entire device is lowered into the well. When the lower end of the 10 tubing engages the bottom 11 of the well, continued downward movement of the fishing tool will bring the ends of the arms 33 into engagement with the tapered lower end 25 of the bore 24 of the combined setting and 15 pulled tool, with the result that these arms are forced toward one another sufficiently to permit the sleeve 38 to pass over the lugs 37 until its downward movement is limited by its engagement with the prongs 36. This will 20 hold the arms collapsed, so that the prongs 36 will readily pass through the ring 28 and the reduction at the upper end of the bore of the setting and pulling tool 23 and the fishing tool may be withdrawn.

25 In pulling the tubing, the fishing tool is lowered into the well with the sleeve 38 loosely surrounding the arms above the lugs 37. As the fishing tool engages in the funnel mouth 27 of the pulling and setting tool, the arms 33 will be slightly drawn together but not sufficiently to permit the sleeve 38 to move downwardly. When the prongs are beneath the level of the ring, movement is reversed and the fishing tool 30 moved upwardly. This causes the ring 28 to move upwardly until it comes into engagement with the shoulder 26 and by its upward movement through the rods 30, the sleeve valve 31 is shifted to open the slot 32 and permit fluid above the upper end of the tubing to 35 return to the well. In event it is found that it is impossible to remove the tubing, it will be obvious that the tool may be disengaged by simply lowering it in the same manner as it is lowered in placing the tubing in position 40 in the well. It will, of course, be obvious that the draining feature hereinbefore set forth is reversely operated during lowering of the tubing into the well, the port at this time 45 being open and permitting passage of fluid collected in the well from a point below to a point above the swab rubber, so that the resistance to movement is materially reduced.

50 Since the construction hereinbefore set forth is capable of a certain range of change and modification without materially departing from the spirit of the invention, I do not limit myself to such specific structure except as hereinafter claimed.

55 I claim:—

1. In well pumping apparatus for pumping wells the casings of which are spaced above the lower ends of the bores thereof, a tubing adapted to extend from the lower end 60 of the well to a point slightly above the lower

end of the casing and having adjacent its upper end means whereby it is sealed to the casing, a valved port in the tubing below said sealing means, the valve of which is normally closed, and means for supporting the tubing 70 section while inserting the same into or removing the same from the well, said supporting means having engagement with the valve maintaining the valve of said port in open position.

2. In well pumping apparatus for pumping wells the casings of which are spaced above the lower ends of the bores thereof, a tubing adapted to extend from the lower end of the well to a point slightly above the lower end 80 of the casing and having adjacent its upper end means whereby it is sealed to the casing, a valved port in the tubing below said sealing means, the valve of which is normally closed, a ring above the upper end of said tubing, a connection between the ring and valve extending through the sealing means, and a fishing member having flexible arms bearing hooks for engagement with said ring to support the tubing in raising or lowering the same within 90 the well.

3. In well pumping apparatus for pumping wells the casings of which are spaced above the lower ends of the bores thereof, a tubing adapted to extend from the lower end 95 of the well to a point slightly above the lower end of the casing and having adjacent its upper end means whereby it is sealed to the casing, a valved port in the tubing below said sealing means, the valve of which is normally closed, a ring above the upper end of said tubing, a connection between the ring and valve extending through the sealing means, a fishing member having flexible arms bearing hooks for engagement with said ring to 100 support the tubing in raising or lowering the same within the well, means operable upon movement of said arms toward one another a predetermined distance for preventing return movement of the arms, and means 105 upon the upper end of the casing below the ring for moving said arms toward one another.

4. In well pumping apparatus for pumping wells the casings of which are spaced above the lower ends of the bores thereof, a tubing adapted to extend from the lower end 110 of the well to a point slightly above the lower end of the casing and having adjacent its upper end means whereby it is sealed to the casing, a valved port in the tubing below said sealing means, the valve of which is normally closed, a ring above the upper end of said tubing, a connection between the ring and valve extending through the sealing means, 115 a fishing member having flexible arms bearing hooks for engagement with said ring to support the tubing in raising or lowering the same within the well, a sleeve surrounding said arms, outstanding lugs on the arms nor- 120 130

5 mally limiting downward movement of the sleeve, and means upon the upper end of the tubing and below said ring having engagement with said arms, moving said arms to-
ward one another upon a predetermined downward movement of the fishing member, said sleeve on surrounding the lugs of the arms maintaining the arms contracted to permit their withdrawal through the ring.

10 5. In well pumping apparatus for pumping wells the casings of which are spaced above the lower ends of the bores thereof, a tubing adapted to extend from the lower end of the well to a point slightly above the lower end of the casing and having adjacent its upper end means whereby it is sealed to the casing, a valved port in the tubing below said sealing means, the valve of which is normally closed, a ring above the upper end of said tubing, a connection between the ring and valve extending through the sealing means, a fishing member having flexible arms bearing hooks for engagement with said ring to support the tubing in raising or lowering the same within the well, and means above the

15 20 25

ring for guiding said fishing member into the ring.

6. In well pumping apparatus for pumping wells the casings of which are spaced above the lower ends of the bores thereof, a tubing adapted to extend from the lower end of the well to a point slightly above the lower end of the casing and having adjacent its upper end means whereby it is sealed to the casing, a valved port in the tubing below said sealing means, the valve of which is normally closed, a ring above the upper end of said tubing, a connection between the ring and valve extending through the sealing means, a fishing member having flexible arms bearing hooks for engagement with said ring to support the tubing in raising or lowering the same within the well, means above the ring for guiding said fishing member into the ring, and springs extending between the ring and said means normally urging the ring downwardly to close said port.

In testimony whereof I hereunto affix my signature.
